UNITED STATES PATENT OFFICE

124,225

DESIGN FOR A COCKTAIL GLASS OR SIMILAR ARTICLE

Charles Sawyer, Toledo, Ohio, assignor to Libbey Glass Company, Toledo, Ohio, a corporation of Ohio

Application May 15, 1940, Serial No. 92,386

Term of patent 7 years

To all whom it may concern:

Be it known that I, Charles Sawyer, a citizen of the United States, residing at Toledo, in the county of Lucas and State of Ohio, have invented a new, original, and ornamental Design for a Cocktail Glass or Similar Article, of which the following is a specification, reference being had to the accompanying drawing, forming a part thereof.

In the drawing:

Fig. 1 is a side elevational view of a cocktail glass showing my new design, the characteristic feature of which is the stem shown in full lines.

Fig. 2 is a sectional view taken along the line
2—2 of Fig. 1 showing the stem contour.

I claim:

The ornamental design for a cocktail glass or similar article, substantially as shown and described.

CHARLES SAWYER.
